UNITED STATES PATENT OFFICE.

ANNA S. FRIDOLPH, OF ZYBACH, TEXAS.

SPRING-CLASP HAIR-FASTENER.

1,089,829.

Specification of Letters Patent. Patented Mar. 10, 1914.

Application filed May 5, 1913. Serial No. 765,578.

To all whom it may concern:

Be it known that I, ANNA S. FRIDOLPH, a citizen of the United States, residing at Zybach, in the county of Wheeler and State of Texas, have invented certain new and useful Improvements in Spring-Clasp Hair-Fasteners, of which the following is a specification, reference being had to the accompanying drawings.

10 This invention relates to improvements in hair fasteners and the primary object of the invention is to provide a fastener which will positively secure a lock of hair in place.

Another object of the invention is to provide a device which is simple and durable in construction, inexpensive to manufacture and one which will be very efficient in use.

With these and other objects in view, the 20 invention consists in the novel features of construction, combination and arrangement of parts as will be hereinafter referred to and more particularly pointed out in the specification and claims.

25 In the accompanying drawing forming a part of this application, Figure 1 is an end elevation of a hair fastener constructed in accordance with an embodiment of my invention with parts broken away. Fig. 2 is a perspective view of the same showing the pin in unlocked position with parts of the covering for the pin broken away. Fig. 3 is a vertical cross section therethrough showing the pin in its locked position. Fig. 4 is a perspective view showing the device in use in the hair. Fig. 5 is an elevation of a slightly modified form of the invention wherein the fastener is applied to an ornament. Fig. 6 is an end elevation of the last 40 mentioned form removed from the ornament. Fig. 7 is a longitudinal section through a still further modified form of the device. Fig. 8 is a perspective view thereof; and Fig. 9 is a perspective view of a further 45 modified form of the invention.

In describing my invention, I shall refer to the drawing in which similar reference characters designate corresponding parts throughout the several views and in which 50 1 indicates the tubular body of the fastener formed preferably of light-weight spring metal, such body being split longitudinally, the resiliency of the body maintaining the edges afforded by the split normally in close proximity. The edges of this body are pref-

erably rolled as shown at 2, to provide a neat-appearing device, while the body 1 itself may be ornamentally designed as desired. One end of said body has a depending tab or tongue 3 formed thereon, with 60 which is hingedly engaged an arcuate pin 4. This pin is covered with a soft material 5, such as rubber, felt or the like and the free end of the same is adapted to be wedged between a pair of spaced apart 65 tabs 6 which are formed integral with the body at the opposite end thereof.

In Figs. 1 and 2 of the drawing, I have shown the covering 5 for the pin 4 as broken away, but it will be understood that this 70 covering is adapted to be extended substantially for the length of said pin.

It will be readily understood that when this device is properly engaged with a lock of hair, and the pin 4 sprung into engagement between said spring tabs 6, the device 75 will be securely clasped in place and may not be displaced except by a manual displacement of the fastener.

It will further be seen that every strand 80 of hair engaged by the device will be securely clasped in its place therein and the hair cannot slip from the pin in view of the tabs at the ends of the body of the device, and particularly in view of the second 85 clamping action had upon the hair by the longitudinal edges afforded by the split.

It will further be seen that the device consists of but two parts, i. e., a body portion and a pin pivoted thereto, affording simplicity and convenience and presenting no 90 parts which will cause the hair to become entangled or severed.

In Figs. 5 and 6, I have shown a slightly modified form of the invention, wherein a 95 body 7 is provided, which is of channel-shaped design in cross section and straight in longitudinal section. This body 7 is secured, in any preferred manner, to an ornament 8, such as a barrette, or the like and 100 the same is provided with a straight pin 9 which is mounted in place similarly to the pin described in connection with the first mentioned form. In this form of the device, the pin thereof is pivotally engaged with a 105 depending tab at one end of the device as in the first mentioned form and the free end of said pin is adapted to be wedged into engagement with a pair of depending tabs formed in the body at the opposite end 110

thereof. In this respect, the device is similar to the first mentioned form and the use thereof will be readily understood.

In Figs. 7 and 8, I have shown a still further modified form of the invention, wherein a body 10 of a design identical to that shown in the first mentioned form is provided. In this form, however, the body is provided with a central opening 11, and the arcuate pin 12 is looped centrally to form an eye or the like 13. When the pin 12 is properly wedged into engagement with the pair of depending tabs on the one end of the body 10, this loop or eye 13 projects through the opening 11. A hair pin 14 of the usual design is then engaged with this projecting loop or eye 13, the device thus being additionally held in the hair through the medium of this pin 14. The device in this form is of slightly smaller proportions than the forms hereabove referred to and is particularly adapted for use in connection with short locks wherein it is absolutely necessary to provide an additional retaining means to secure the device in the hair. When this form of device is properly applied to use, the same is practically invisible as it is quite small and fastens under the coils of the hair.

In Fig. 9, I have shown a still further modified form of the device which gives a side-comb effect, when in use. The same consists of a channel-shaped body 15, which is flattened and has a portion of the top thereof removed to provide a rectangular opening 16 therein. The free edges of the material forming the body 1, are spaced apart to provide a channel-way therebetween as in the above mentioned forms and one end of the material forming the body is provided with a tab 17 for the pivotal engagement therewith of a pin 18. This pin 18 consists of a spring wire looped upon itself and having the sections of the wire forming the main body portion spread apart as shown at 19. The spread apart portion of the pin 19 is of greater width than the channel between the free edges of the material forming the body and when the pin 15 is drawn against the body the spread apart portion of the former must necessarily yield in order to permit said pin to be sprung into position through the channel-way of the body. As soon as the pin has been forced through the channel of said body, the portions of the pin will again take their initial form and spread to the design as shown in dotted lines in Fig. 9. The pin will, therefore, be automatically retained in its locked position and the hair engaged between the pin and body portion of the device will be securely fastened and disclosed through the opening in the body. This form of the de-

vice, as stated above, is used in place of a side-comb giving the effect of the latter 65 when in use.

From the foregoing it will be seen that I have provided an improved fastener which will be a valuable addition to the ladies' 70 toilet and which will be a very satisfactory convenience in curling and dressing the hair.

It will also be seen that this device is adapted to supersede the use of the well known side combs and barrettes now in use and it will still further be seen that this device is one which, when once clamped in position may not be detached except by manual operation.

It will still further be seen that the device is simple and durable in construction, inexpensive to manufacture and one which will be very efficient and useful in operation.

While I have particularly described the elements best adapted to perform the functions set forth, it is obvious that various 85 changes in form, proportion and in the minor details of construction may be resorted to without departing from the spirit or sacrificing any of the principles of the invention.

Having thus described this invention, what is claimed is:—

1. A device of the character described comprising an elongated tubular member split longitudinally, said member possessing 95 such resiliency as to maintain the longitudinal edges afforded by the split normally in close proximity, a pin operatively connected to the body at a side opposite to the split, such pin being adapted to be passed through 100 the split, and means carried by the side of the member opposite to the split for maintaining the pin within the tubular member and in close proximity to the wall thereof.

2. A device of the character described comprising an elongated tubular member split longitudinally, said member possessing such resiliency as to maintain the longitudinal edges afforded by the split normally in close proximity, inwardly disposed tabs 110 carried by the body at a side opposite to the split and adjacent the ends thereof, such tabs obstructing the bore of the member and a pin hingedly connected to one of the tabs and adapted to be passed through the 115 split, the second of such tabs being provided with means for maintaining the pin within the tubular member and in close proximity to the wall thereof.

In testimony whereof I hereunto affix my 120 signature in the presence of two witnesses.

ANNA S. FRIDOLPH.
